UNITED STATES PATENT OFFICE.

AUSTIN E. MILLER, OF RURAL RETREAT, VIRGINIA.

ROTARY ENGINE.

No. 907,843.

Specification of Letters Patent.

Patented Dec. 29, 1908.

Application filed May 8, 1908. Serial No. 431,640.

To all whom it may concern:

Be it known that I, AUSTIN E. MILLER, a citizen of the United States, residing at Rural Retreat, in the county of Wythe and State of Virginia, have invented a new and useful Rotary Engine, of which the following is a specification.

This invention relates to rotary engines with special reference to rotary engines 10 of the compound type.

The invention further relates to combined rotary engines and turbines.

One object of the invention is to provide an improved general construction of a 15 rotary engine.

Another object of the invention is to provide a sliding piston of improved form actuated by the steam pressure.

A still further object of the invention is to 20 provide an improved form of combined rotary engine and turbine in which the exhaust fluid pressure from the rotary engine will be utilized to actuate the turbine.

The invention consists in general of a 25 rotary engine mounted in connection with a turbine, said rotary engine being provided with exhaust ports and passages leading to the nozzle of a turbine mounted upon the same shaft.

30 The invention further consists in such novel details of arrangement, and combination of parts hereinafter fully described, illustrated in the accompanying drawings, and specifically set forth in the claims.

35 In the accompanying drawings like characters of reference indicate like parts in several views.

Figure 1 is a side elevation of an engine constructed in accordance with this invention. Fig. 2 is an end elevation thereof. Fig. 3 is a vertical section of the invention showing the valve and sliding piston arrangement in the rotary engine. Fig. 4 is a transverse section partly in elevation 45 showing the arrangement of rotary engine and turbine. Fig. 5 is a partial sectional view through the turbine showing the nozzle, blades, and exhaust.

The numeral 10 indicates a cylindrical 50 casing in which the rotary parts are held to move. Upon either side of the casing 10 are heads 11 provided with apertured lugs 12 and downwardly extending portions 13 being arranged to form a base or frame for 55 said engine.

Within the apertured lugs 12 are held

bolts 14 which serve to draw the two heads tightly together and against the cylindrical casing 10. A shaft 15 passes through suitable bearings in the heads 11 and is held to 60 revolve therein.

The rotor preferably consists of a turbine portion 16 provided with a pair of laterally arranged extensions 17 which serve to constitute the revolving elements of the rotary 65 engine.

The rotor is provided with ribs 18 of annular form arranged to contact with the cylindrical casing 10 and thus prevent the escape of steam from one port to the other. The 70 central portion of the rotor which lies within the turbine is in the form of a solid web and is keyed securely to the shaft 15 as best seen in Fig. 5. The portions 17 of the rotor are centrally recessed as shown in Fig. 3 and 75 each of said portions is provided with steam passages 19 having enlarged shouldered portions 20. It is preferred that the steam passages in one of the portions 17 shall lie at right angles to the steam passages in the 80 other portions 17 as indicated by the dotted and full lines in Fig. 3. Rigidly attached to each of the plates forming the heads 11 is a boss 21 which extends within the recess in the center of the portion 17. The boss 21 is 85 provided with arms 22 arranged to contact with the side walls of said recess. By the peculiar arrangement of the lugs 22 the central recesses are each divided into four parts two of which form steam passages 23 and the 90 other two exhaust passages 24.

Between the casing 10 and the rotor portions 17 are formed annular spaces 25 which are broken by fixed abutments 26 preferably disposed opposite each other and provided 95 with an inclined face 27. Held within and closely fitting the passages 19 and 20 are pistons 28 having shouldered portions 29 which lie within the portion 20 of the recess. The shouldered portions 29 are of less length 100 than the portion 20 of the recess and it is therefore possible for the piston to slide in and out, the motion being limited by the co-action of the shouldered portion 29 and enlarged portion 20 of the recess. The piston 105 28 is hollow as indicated at 30 and is provided with an opening 31 arranged to permit the passage of steam through the piston and into the annular recess 25. Fixedly mounted within the piston 28 is a perforated plate 32 110 whereon is fixed a pin 33. Upon the pin 33 is slidably mounted a valve 34. Opening

into the recess 23 is a steam port 35 which is supplied with steam by means of a pipe 36. There is of course one of these steam pipes and ports for each of the recesses 23. Opening 5 from each of the recesses 24 is an exhaust port 37 which connects with an exhaust pipe 38 by means of which the exhaust is led away to any suitable point. In the casing 10 adjacent each of the abutments 26 is a port 39 which communicates with a passage 40 formed on the exterior of said casing. This passage 40 is so positioned as to conduct the steam passing thereto to a nozzle 41 lying adjacent the path of the turbine blades 42. 10 Exhaust ports 43 are also formed in the casing one of said ports being rearwardly disposed with reference to each of the nozzles 41. The exhaust ports 43 communicate with exhaust pipes 44 which may connect 15 with the exhaust pipes 38 or be separate as desired.

In the operation of the device steam is admitted to the steam pipes 36 ports 35 and passage 23. From the passage 23 the steam 20 passes through the recess 19 and the hollow pistons, the valve 34 being forced open by pressure of the steam. The steam then passes out of the opening 31 and causes the rotor to move. It is to be observed that 25 while the steam is passing through the hollow piston a certain amount of pressure will continue to be exerted against the valve 34 and the piston will thus be forced outward against the casing 10. The continuance of 30 the revolution brings the passage 19 opposite one of the lugs 22 and then opposite the exhaust passage 24. When the piston arrives at this point steam is exhausted through the ports 37 and pipes 38. The valves 34 will 35 then close, and, the pressure having been removed the pistons 28 will no longer be forced out against the casing 10 but will be readily forced back by the inclined face 27 of the abutment 26. As soon, however, as the 40 piston passes the stationary abutment, the steam will again open the valve 34 and forces the piston out again the casing 10. Meanwhile the exhaust steam ahead of the piston 45 has been forced outward through the steam ports 39 and passage 40 and into the nozzle 41 where it serves to actuate the turbine element. This steam after acting upon the turbine element is exhausted through the port 43 and pipe 44. 50 It is obvious that on some forms of the engine one of the pistons 28 with the corresponding parts may be omitted and also that on larger engines, where desirable, the num-

ber of pistons, 28 and corresponding parts may be increased without affecting the scope 60 of the invention.

Having thus described the invention what is claimed as new is:—

1. In an engine of the class described, a rotor comprising a central turbine member 65 and a pair of laterally disposed piston actuated members rigidly connected thereto, and a casing having inlet ports to admit steam to the piston actuated members of the rotor, exhaust ports leading from said members, 70 nozzles to admit steam to said turbines, steam passages connected with the exhaust ports and nozzles, and other exhaust ports leading from said turbines.

2. In an engine of the class described, a 75 rotor having a central recess and a passage therefrom to the periphery of said rotor, a hollow piston held to slide in said passage, a perforated disk in said piston, a boss held in said recess to form steam and exhaust passages, a casing carrying said boss provided with inlet ports opening into said steam passages, exhaust ports from said exhaust passages and other peripheral exhaust ports, and a stationary abutment. 80

3. In an engine of the class described, a rotor having a central recess and a passage therefrom to the periphery of said rotor, a hollow piston held to slide in said passage, a perforated disk in said piston, valves in said 90 pistons, a boss held in said recess to form steam and exhaust passages, a casing carrying said boss provided with inlet ports opening into said steam passages, exhaust ports from said exhaust passages and other peripheral 95 exhaust ports, and a stationary abutment.

4. In an engine of the class described, a rotor having a central recess and a passage therefrom to the periphery of said rotor, a 100 hollow piston held to slide in said passage, a perforated disk in said piston, a pin mounted on said disk, a valve slidably mounted on said pin, a boss held in said recess to form steam and exhaust passages, a casing carrying 105 said boss provided with ports opening into said steam passages, exhaust ports from said exhaust passages and other peripheral exhaust ports, and a stationary abutment.

In testimony that I claim the foregoing as 110 my own, I have hereto affixed my signature in the presence of two witnesses.

AUSTIN E. MILLER.
